ADJUSTABLE HEIGHT INCREASING SHOE

Joseph Burger, New York, N. Y.

Application March 25, 1940, Serial No. 325,710

6 Claims. (Cl. 36—71)

This invention relates to improvements in shoes for men and women and consists of a novel addition and arrangement embodied in the shoes of regular or conventional types to be worn by human feet, the principal purpose of which is to have the wearer of these shoes appear taller.

The principal object of this invention is to provide an inner sole for a shoe combined with a metallic arch including a vertically adjustable means supporting the heel portion of the arch and inner sole which adjustable means is mounted in the heel of the shoe in a manner as to be adjustable exteriorly or interiorly or both of the shoe to thereby vary the height to which the heel portion of the inner sole and arch may be raised.

A still further object of the invention relates to the provision of the adjusting means for the adjustable support in the heel part of the shoe and exteriorly or interiorly or both thereof and so positioned relative to said heel as to permit of a manual operation of the adjusting means while the shoe is being worn and without removal thereof.

Another object of the invention relates to the provision of an inner sole embodying a novel metallic arch affixed to the underside thereof such as to permit of a maximum of flexibility in said inner sole when inserting the same into the shoe or if said inner sole is permanently affixed to the shoe to permit elevation of the heel and arch portions thereof in the adjustment of the same or for repair or inspection purposes.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Figure 1 is a longitudinal sectional view through the shoe.

Figure 2 is a bottom view of the invention showing a section on line 2—2 of Figure 1.

Figure 3 is a sectional view on line 3—3 of Figure 1.

Figure 4 is a bottom view of the shoe insert or inner sole.

Referring to the drawing, 10 denotes a conventional form of shoe comprising a sole 11, heel 12, upper 13, and inner sole or insert 15. The inner

sole 15 may be fixed in any desired manner at its sole portion to the shoe or the same may be utilized as an insert with the sole portion thereof adapted for insertion into a pocket provided within the shoe at the sole position thereof such as shown and described in my Patent No. 2,194,637, granted March 26, 1940.

In any event, the inner sole 15 is formed in any desired manner of leather or laminations of leather and fabric and is provided on its under side with a metallic arch unit 16 comprising a forward metallic plate support 17, a metallic arch 18, and a heel plate 19. Each of the members of the arch unit 16 is shaped so as to fit within the confines or configuration of the inner sole, see Figure 4, and each is rigidly secured centrally thereof to said inner sole 15 as by the rivets 19a, 20 and 21, respectively.

The metal arch 18 is provided with longitudinally extending tongues 23 and 24 respectively at its front and rear ends each adapted to overlap, respectively, the forward plate support 17 and heel support 19. Preferably the front and rear end edges 25 and 26 are inclined so as to nest within the complementary edges 25a and 26a of the forward plate support 17 and heel support 19, said edges being arranged in juxtaposed relation to each other so as to retain all of the parts of the metal arch 16 in alignment with each other at all times. By virtue of the arch tongues 23 and 24 overlapping and engaging the front plate support 17 and heel support 19 a rigid arch is provided for the support of the foot, while at the same time flexibility of the inner sole 15 is permitted along portions thereof between the rivets 19a, 20 and 21 in a direction away from said arch unit 16. Thus for example the heel portion 15a of the inner sole 15 carrying the heel support plate 19 along with the metal arch 18 may be raised or flexed to permit access to the part of the shoe therebeneath.

The adjusting mechanism for elevating or depressing the heel portion 15a of the inner sole 15 comprises a screw 30 and a nut 31. The screw 30 is formed to provide a disc-like head 32 and an axial threaded shank 33, the head 32 being adapted to engage the underside of the metal arch 18 and said shank 33 projecting downwardly and outwardly of said shoe through the opening 34 into a part cylindrical vertical recess 35 provided in the heel 12 in the central forward portion thereof. Axially inserted into the part cylindrical recess 35 for threaded engagement with the shank 33 is the nut 31 which is cylindrical in shape and of a diameter slightly less than 55

that of said recess whereby to be freely turnable therein. It will be noted that a portion of the cylindrical nut 31 will project forwardly out of the part cylindrical recess 35 as clearly shown 5 in Figure 2.

In order to retain the nut 31 in said recess 35 as well as to prevent axial movement thereof the same is provided with an intermediate peripheral groove 36 which is adapted to seat the arms 37 10 of a U-plate 38 which straddles said nut, the U-plate 38 being positioned between the leather lifts 12^a and 12^b of the heel 12, see Figure 1. If desired the lift 12^b may be a rubber heel. The U-plate 38 is rigidly secured in position to the 15 upper lift 12^a as by the nails 39. Preferably the cylindrical surface of the nut 31 is roughened or serrated to facilitate rotation thereof.

It is thus seen that the nut 31 can be rotated as by the thumb moving thereagainst to turn the 20 same without removing the shoe. As the nut 31 is permitted only rotational movement the screw 30 must be held from turning so as to provide the desired up and down axial movement thereof. There is thus provided on the underside of the 25 metal arch 18 a lug 40 which is adapted to enter an opening 41 provided in the screw-head 32. This structure obviously can be reversed, i. e. the lug placed on the disc-head 32 and the opening receiving said lug provided in the metal arch 18, 30 or if desired the disc-head 32 may be rigidly secured to said metal arch 18 as by rivets.

It is therefore apparent from the above described construction that the wearer of shoes provided with said described height increasing 35 means may readily adjust the same to meet his individual requirements by the simple expedient of rotating the cylindrically exposed portion of the nut 31.

It will be further noted that the heel 12 is provided with the usual top piece 12^c which is made 40 of any desirable material. This top piece 12^c covers the underside of the nut 31 and bottom end of screw 30, so that only the side portion 45 of the nut 31 is exposed to view at the breast line of the heel 12.

Having thus described my invention, I claim as new and desire to secure by Letters Patent:

1. In a shoe including a heel, a support for increasing the apparent height of a person comprising an inner sole including an arch and heel portion, support means connected to said arch and heel portion and having a threaded shank projecting downwardly and outwardly of said shoe into a part cylindrical recess formed in said heel, and cylindrical nut means carried within said recess threadedly engaging said shank and adapted upon manipulation of the cylindrical surface thereof to impart a vertical up or down movement to said support means.

2. In a shoe including a heel, an adjustable support for increasing the apparent height of a person comprising an inner sole, a metallic arch unit attached to the underside of said inner sole, screw means comprising a head fixed to said arch unit and a threaded shank adapted to project downwardly and outwardly of said shoe into a part cylindrical recess formed in the forward central portion of said heel, and a cylindrical nut threadedly engaging said shank positioned within 70 said part cylindrical recess and having a portion thereof projecting exteriorly of said recess and heel to provide an exposed part cylindrical surface adapted to be manually manipulated exteriorly of said heel to effect rotation of said nut whereby to axially move said screw means.

3. In a shoe including a heel, an adjustable support for increasing the apparent height of a person comprising an inner sole, a metallic arch unit attached to the underside of said inner sole, screw means comprising a head fixed to said 5 arch unit and a threaded shank adapted to project downwardly and outwardly of said shoe into a part cylindrical recess formed in the forward central portion of said heel, and a cylindrical nut threadedly engaging said shank positioned within 10 said part cylindrical recess and having a portion thereof projecting exteriorly of said recess and heel, to provide an exposed part cylindrical surface adapted to be manually manipulated exteriorly of said heel to effect rotation of said nut 15 whereby to axially move said screw means, said metallic arch unit comprising a forward plate support, an intermediate arch and a heel plate support each individually secured to said inner sole, and said screw means head being non-rotatable 20 connected to said intermediate arch.

4. In a shoe including a heel, an adjustable support for increasing the apparent height of a person comprising an inner sole, a metallic arch unit attached to the underside of said inner sole, 25 screw means comprising a head fixed to said arch unit and a threaded shank adapted to project downwardly and outwardly of said shoe into a part cylindrical recess formed in the forward central portion of said heel, and a cylindrical nut 30 threadedly engaging said shank positioned within said part cylindrical recess and having a portion thereof projecting exteriorly of said recess and heel, to provide an exposed part cylindrical surface adapted to be manually manipulated exteriorly of said heel to effect rotation of said nut 35 whereby to axially move said screw means, said cylindrical nut being provided with a peripheral groove intermediate its ends, a U-plate rigidly mounted within said heel with the arms thereof 40 straddling said nut and seated in said groove whereby only rotational movement of said nut is permitted.

5. In a shoe including a heel, an adjustable support for increasing the apparent height of a 45 person comprising an inner sole, a metallic arch unit attached to the underside of said inner sole, screw means comprising a head fixed to said arch unit and a threaded shank adapted to project downwardly and outwardly of said shoe into a 50 part cylindrical recess formed in the forward central portion of said heel, and a cylindrical nut threadedly engaging said shank positioned within said part cylindrical recess and having a portion thereof projecting exteriorly of said recess and heel to provide an exposed part cylindrical 55 surface adapted to be manually manipulated exteriorly of said heel to effect rotation of said nut whereby to axially move said screw means, said metallic arch unit comprising a forward plate 60 support, an intermediate arch and a heel plate support each arranged in juxtaposed relation to each other and individually secured to said inner sole, tongue means on each end of said intermediate arch overlapping the underside of said 65 forward plate and heel plate whereby said inner sole may be flexed in the region of said arch unit in a direction away from the same, a lug depending from said intermediate arch, and said screw means head having an opening adapted 70 to receive said lug whereby to prevent rotation of said screw means.

6. In a shoe including a heel, an adjustable support for increasing the apparent height of a person comprising an inner sole, a metallic arch 75

unit attached to the underside of said inner sole, screw means comprising a head fixed to said arch unit and a threaded shank adapted to project downwardly and outwardly of said shoe into a part cylindrical recess formed in the forward central portion of said heel, and a cylindrical nut threadedly engaging said shank positioned within said part cylindrical recess and having a portion thereof projecting exteriorly of said recess and heel to provide an exposed part cylindrical surface adapted to be manually manipulated exteriorly of said heel to effect rotation of said nut whereby to axially move said screw means, said metallic arch unit comprising a forward plate support, an intermediate arch and a heel plate support each arranged in juxtaposed relation to

each other and individually secured to said inner sole, tongue means on each end of said intermediate arch overlapping the underside of said forward plate and heel plate whereby said inner sole may be flexed in the region of said arch unit in a direction away from the same, a lug depending from said intermediate arch, and said screw means head having an opening adapted to receive said lug whereby to prevent rotation of said screw means, said cylindrical nut being provided with a peripheral groove intermediate its ends, a U-plate rigidly mounted within said heel with the arms thereof straddling said nut and seated in said groove whereby only rotational movement of said nut is permitted. 15
